UNITED STATES PATENT OFFICE.

JOHN TOTH, OF JOLIET, ILLINOIS.

SWITCH-THROWING DEVICE.

1,071,826.

Specification of Letters Patent.

Patented Sept. 2, 1913.

Application filed April 20, 1911. Serial No. 622,239.

To all whom it may concern:

Be it known that I, JOHN TOTH, a subject of the King of Hungary, residing at Joliet, in the county of Will and State of Illinois, have invented certain new and useful Improvements in Switch-Throwing Devices, of which the following is a specification, reference being had therein to the accompanying drawing.

10 This invention relates to a switch throwing device, and the objects of my invention are to provide automatic means for throwing a switch while a train is in motion, and novel means for restoring the switch to 15 its normal position after a train has passed over the same.

Other objects of my invention are to provide a switch throwing device that can be used in connection with a semaphore or 20 visible signal, and to accomplish the above results by a device that is simple in construction, applicable to the present type of railroad equipment and highly efficient for insuring the safe passage of trains over 25 tracks.

With the above and other objects in view, the invention resides in the novel construction, combination and arrangement of parts to be hereinafter specifically described and 30 then claimed, and reference will now be had to the drawings, wherein:—

Figure 1 is a plan of a switch throwing device in accordance with this invention, Fig. 2 is an enlarged plan of the track equipment, Fig. 3 is a longitudinal sectional view of the same, Fig. 4 is a front elevation of the train equipment, Fig. 5 is a side elevation of the same, Fig. 6 is an enlarged vertical sectional view of a signal forming part 40 of the switch throwing device, and Fig. 7 is a longitudinal sectional view of the same.

The reference numeral 1 denotes ties or sleepers adapted to support rails 2 and 3, the rails 2 representing a main track and 45 the rails 3 the same track or a siding track located some distance from the main track 2, in order to provide sufficient space for a switch adapted to control the passage of a train on the main and siding tracks.

50 Mounted upon the ties 1 between the main rails 2 are the lateral flanges 4 of a casing 5 adapted to fit between the ties 1. The casing 5 has a semicircular recess 6 and mounted upon said casing at the sides of the 55 recess 6 are bearings 7 for a shaft 8, said shaft extending through one of the main

rails 2 into bearings 9, carried by a frame 10 located to one side of the main track.

Mounted upon the shaft 8 in the recess 6 is an auxiliary actuating wheel 11 having 60 a plurality of equally spaced radially disposed arms 12 and an integral pinion 13. The pinion 13 can have circumferentially arranged teeth or conform to a sector-gear, the former being preferable, said pinion 65 meshing with a longitudinal rack 14 movably mounted upon rollers 15 arranged in sockets 16 provided therefor in the casing 5. The casing has longitudinally alining 70 openings 17 providing clearance for the rack 14. The rack 14 is pivotally connected, as at 18 to a reach-rod 19. The rod 19 is pivotally connected, as at 20 to a lever 21 fulcrumed upon a pin 22 mounted transversely of an extension 23 of a casing 24. 75 The casing 24 is located between the rails 3 and has a recess 25, similar to the casing 5.

Mounted upon the casing 24 are bearings 26 for a shaft 27 and mounted upon the shaft 27 is a main actuating wheel 28 having 80 radially disposed arms 29 corresponding in number to the arms 12 of the actuating wheel 11. The shaft 27 has a crank 30 and this crank is pivotally connected by a rod 31 to the lever 21. The rod 31 extends 85 through an opening 33 provided therefor in the casing 24.

The shaft 8 within the frame 10 has crank portions 33 and 34 and these crank portions are connected by links 35 to rods 90 36 which are connected, as at 37 to racks 38 and 39. The racks 38 and 39 extend through openings provided therefor in a housing 40 mounted upon a base 41, adjacent to the juncture of the rails 2 and 3 or 95 at the switch controlling the passage of a train over said rails. The racks are movably supported upon rollers 42 arranged in bearings 43, carried by the base 41, and said racks mesh with large pinions 44 and 45 100 loosely mounted upon a shaft 46 mounted in a bearing 47 provided therefor in the housing 40. The loosely mounted pinions have the confronting faces thereof provided with sector-gears 48 and these gears mesh with a 105 horizontal beveled gear wheel 49 mounted upon a vertical signal shaft 50 rotatably supported by the bearing 47. The upper end of the shaft extends through an opening 51 provided therefor in the housing 40, 110 said shaft having balance arms and a visible signal or lantern 53. The lower end of

the shaft is revolvably supported in a bearing 54 provided therefor in the base 41, and mounted upon the lower end of the shaft is a disk 55 to which can be connected a switch 5 throwing rod 56 for throwing the switch heretofore mentioned and not shown.

The train or locomotive equipment comprises a suitable bracket 57 adapted to be carried by a locomotive or car. Mounted 10 upon the bracket 57 is a bearing 58 for a shaft 59. The shaft 59 is provided with a weighted arm 60, an L-shaped arm including a longitudinally extending portion 61 and a horizontally disposed portion 61^a and 15 a lever 62. The lever 62 extends through a curved guide 63, carried by the support 64 of the bracket 57. The curved guide 63 has flat springs 65 upon the inner side thereof and at the ends for holding the lever 62 in 20 an adjusted position.

To throw the switch tongue, the lever 62 is swung to the upper ends of the guides 63 and is held thereby with the L-shaped arm lowered. The horizontal portion 61^a of the 25 L-shaped arm is then in the path of one of the arms 29 of the actuating wheel 28 of the track equipment. When one of the arms 29 is struck, by the horizontal portion 61^a of the L-shaped arm the actuating wheel 30 28 is partially rotated, and through the medium of the rods 31 and 19 and the lever 21, the rack 14 is shifted. When this rack is 35 shifted the actuating wheel 11 is moved to rotate the shaft 8, and as said shaft is rotated, the racks 38 and 39 are moved. These racks through the medium of the pinions 44 and 45, sector gears 48 and gear wheel 49 partially rotate the shaft 50. In 40 partially rotating the shaft 50, the switch tongue is thrown through the medium of the rod 56 and the signal 53 is set.

As the actuating wheel 11 is located some distance from the wheel 28, the actuating wheel 11 will not be engaged by the horizontal portion 61^a of the L-shaped arm until 45 the locomotive or train has passed over the

switch. Then the wheel 11 will be actuated to restore the switch tongue and the signal to their normal position.

It is thought that the operation and utility of the switch throwing device will be apparent without further description, and while in the drawings there is illustrated a preferred embodiment of the invention, it is to be understood that the structural elements thereof are susceptible to such changes as fall within the scope of the appended claims.

What I claim is:—

A switch throwing device comprising a main and an auxiliary actuating wheel spaced from each other and adapted to be operated in unison, radial contact arms projecting from each of said actuating wheels, casings with basin shaped sockets therein, 65 said wheels trunnioned upon the tops of said casings and extending within said sockets, the casing of said main wheel having alining openings therethrough communicating with said socket, said auxiliary 70 wheel provided with a reduced side having teeth conforming to a sector-gear, a longitudinal rack engaging with said teeth and extending through said openings, a reach rod connected to said rack, a lever pivoted 75 at one end to said reach rod, a shaft upon which said main actuating wheel is mounted, a crank projecting from said shaft, a rod attached to said crank and to the other arm of said lever, a vertically disposed 80 switch rod operating shaft, and an operative connection between said last mentioned shaft and said auxiliary wheel for shifting said shaft when the wheels are actuated by means carried by a traveling vehicle. 85

In testimony whereof I affix my signature in the presence of two witnesses.

JOHN TOTH.
